FAN MOTOR SUPPORT

Edwin F. Guth, Webster Groves, Mo.

Application March 20, 1934, Serial No. 716,486

2 Claims. (Cl. 248—18)

My invention relates to motors which are employed to rotate so called ceiling fans which are frequently used in connection with lighting fixtures.

5 In use various objectionable features have been observed unless some form of cushioning device is employed, the vibrations of the motor are transmitted to the ceiling causing a disagreeable noise in the room above. This has been 10 overcome by providing a vertically yieldable spring support.

Another objection is that the motor vibrations due to starting torque and running, are transmitted to the lamps in the lighting fixture. Thus 15 it has the result of greatly shortening the life of the lamps.

My invention has for its principal object to provide a fan motor support which will absorb all internal and external vibrations thus protecting the fixture and insuring longer life of the lamps.

A further object is to provide convenient means for mounting the electric lamp sockets on the frame of the fan motor support.

25 A further object is to so construct my fan motor support that if it breaks the motor will not fall.

My means of accomplishing the foregoing objects may be more readily understood by having 30 reference to the accompanying drawings which are hereunto annexed and are a part of this specification, in which—

Fig. 1 is a top or plan view of my improved fan motor support;

35 Fig. 2 is a side elevation;

Fig. 3 is a plan view of a modified form in which a single spring is used; and

Fig. 4 is a vertical sectional view of the same.

Similar reference numerals refer to similar 40 parts throughout the entire description.

As shown in the drawings, a stem 1 may be secured to a standard outlet box (not shown) in the usual manner, the lower end 3 of the stem 1 is threaded onto a central hub 4 as shown 45 in Fig. 2 formed on a frame 5 which carries my improved fan motor support and which may also, if desired, carry electric light sockets when a lighting fixture is combined with a fan. This frame 5 is provided with four receptacles 6, 7, 50 8 and 9 which are adapted to receive conoidal coil springs 10. As these receptacles and springs are identical I shall only describe one of them. These springs 10 are constructed so that each succeeding convolution will be smaller than the 55 one below it yet its external diameter will be

sufficiently greater than the one below it to prevent it from telescoping it. From the apex of each of the springs 10 depends a screw 11, the head of which rests upon the top convolution. In some cases it may be found desirable to insert 5 a washer intermediate the head of the screw 11 and the apex of the spring 10. Each receptacle is provided with a central opening 13 at its bottom providing an inwardly extending flange 14 upon which the bottom convolution of the spring 10 rests, the circular walls 15 of the receptacles about the lower convolution or base of the conoidal springs 10 and serve to prevent any horizontal movement of the base of the spring 10. The lower portion of the screw 11 is, as clearly seen 15 in the sectional view, spaced from the edges of the inwardly extending flange 13 and the base of the spring 10 so that it is free to move horizontally in any direction, the end 16 of the screw 10 is screwed into the upper plate 17 of the fan 20 motor 18. It will be clear from the foregoing that the plurality of conoidal coil springs 10 cushion the motor suspension screws 11 while permitting them to move both vertically and horizontally thus effectually absorbing the vibrations of the fan motor 18. If it is desired to 25 combine the lighting fixture with the fan radially extending arms 19 may be cast or secured to the frame 5 and standard electric light sockets 20 may be secured thereto by means of screws 21 30 in the usual or customary manner.

It will be seen from the foregoing description that should a spring break still the motor will not fall because the succeeding convolutions are formed of too large a diameter to go through 35 the next lower coil so the screw would still be in place though the cushioning effect of the spring were destroyed.

It may, under some circumstances, be found desirable to employ a conoidal shaped elastic and compressible cushion formed of some other material than spring wire and I do not wish to be understood as limiting myself thereto except as such limitations appear in the claims.

As shown in Figs. 3 and 4, only a single spring 45 is used, this spring is mounted in a cup shaped receptacle 23 having an opening 24 in its bottom. The receptacle may be provided with arms 25, 26 and 27 for supporting the electric light sockets (not shown). In this case the receptacle is secured to a bushing 28, which is screwed onto the stem by means of screws 30 which pass through the walls of the receptacle and into the bushing as clearly shown in Fig. 4. In this construction it is better to use a stud 31 provided 50 55

with a hexagon head which has a slot 32 to receive one end of the spring 33, the other end 34 being secured in a slot formed in the bottom of the receptacle 23. The stud 31 is 5 screwed into the motor housing. In operation it is obvious it will be the same as the springs in Figs. 1 and 2.

Having described my invention what I regard as new and desire to secure by Letters Patent is:

- 10 1. In a fan motor suspension, the combination of a frame adapted to be attached to a ceiling, a vertical motor shaft located below the frame, the frame having a plurality of recesses located in concentric relation with the motor shaft, there being an opening in the bottom wall of each of said recesses, a conoidal spring mounted in each of said recesses, a screw suspended 15 from the apex of each spring, said screws ex-

tended through said openings and being spaced from the edges thereof and extended into the end plate of the motor.

2. In a fan motor suspension, the combination of a frame adapted to be attached to a ceiling, 5 a vertical motor shaft located below the frame, the frame having a plurality of recesses located in concentric relation with the motor shaft, there being an opening in the bottom wall of each of said recesses, a conoidal spring mounted to each 10 of said recesses, the lower coil abutting the walls of the recesses and thus being held against horizontal movement, a screw suspended from the apex of each spring, said screws extended through said openings and being spaced from the edges 15 therein and extending into the end plate of the motor.

EDWIN F. GUTH.
